[57] **CLAIM**

The ornamental design for measuring tool with a sliding leveler, as shown and described.

DESCRIPTION

FIG. 1 is a front perspective view of the measuring tool with sliding leveler showing my new design;
FIG. 2 is a top plan view thereof;

FIG. 3 is a rear elevational view thereof;
FIG. 4 is a side elevational view thereof;
FIG. 5 is a front elevational view thereof;
FIG. 6 is a bottom plan view thereof;
FIG. 7 is a front perspective view thereof of an alternate embodiment of FIG. 1;
FIG. 8 is a front perspective view thereof of an alternate embodiment of FIG. 1;
FIG. 9 is a front perspective view thereof of an alternate embodiment of FIG. 1;
FIG. 10 is a front perspective view thereof of an alternate embodiment of FIG. 1;
FIG. 11 is a front perspective view thereof of an alternate embodiment;
FIG. 12 is a front elevational view thereof of an alternate embodiment of FIG. 1;
FIG. 13 is a rear elevational view of FIG. 12;
FIG. 14 is a top plan view of FIG. 12;
FIG. 15 is a side elevational view of FIG. 12;
FIG. 16 is a bottom plan view of FIG. 12;
FIG. 17 is a front perspective view thereof of an alternate embodiment of FIG. 12;
FIG. 18 is a front perspective view thereof of an alternate embodiment of FIG. 12;
FIG. 19 is a front perspective view thereof of an alternate embodiment of FIG. 12;
FIG. 20 is a front perspective view thereof of an alternate embodiment of FIG. 12;
FIG. 21 is a front perspective view thereof of an alternate embodiment of FIG. 1;
FIG. 22 is a top plan view thereof of FIG. 21;
FIG. 23 is a rear elevational view thereof of FIG. 21;
FIG. 24 is a side elevational view thereof of FIG. 21;
FIG. 25 is a front elevational view thereof of FIG. 21;
FIG. 26 is a bottom plan view thereof of FIG. 21;
FIG. 27 is a front perspective view thereof of an alternate embodiment of FIG. 21; and,
FIG. 28 is a front perspective view thereof of an alternate embodiment of FIG. 21.
